UNITED STATES PATENT OFFICE.

JAMES L. GLAWSON, OF AMERICUS, GEORGIA, ASSIGNOR OF ONE-HALF TO HIRAM W. KNOWLTON, OF AMERICUS, GEORGIA.

EXTENSION-HARROW.

1,141,330.

Specification of Letters Patent.

Patented June 1, 1915.

Application filed August 27, 1913. Serial No. 786,964.

To all whom it may concern:

Be it known that I, JAMES L. GLAWSON, a citizen of the United States, residing at Americus, in the county of Sumter, State of Georgia, have invented certain new and useful Improvements in Extension-Harrows; and I do hereby declare the following to be a full, clear, and exact description of the invention, such as will enable others skilled in the art to which it appertains to make and use the same.

This invention relates to harrows, particularly to that type in which means are provided for withdrawing the teeth and protruding skids for convenience in transportation and has for its object the provision of a novel construction of harrow frame whereby a plurality of harrows may be placed side by side and secured to each other for forming a gang.

A further object is to provide an extremely simple harrow that will be formed of a few strong and durable parts that will not easily get out of order.

With the above objects in view the invention consists of certain novel details of construction and combination of parts hereinafter fully described and claimed, it being understood that various modifications may be made in the minor details of construction within the scope of the appended claim.

In the accompanying drawing illustrating this invention: Figure 1 is a plan view of the harrow. Fig. 2 is a side elevation. Fig. 3 is a longitudinal sectional view. Fig. 4 is a cross sectional view on the line 4—4 Fig. 1. Fig. 5 is a fragmentary horizontal sectional view showing the means of securing the teeth. Fig. 6 is a sectional view on the line 6—6 Fig. 2.

Referring now to the drawing in which like characters of reference designate similar parts, the harrow is shown to be triangular in form and comprises angleiron side rails 10 that are preferably formed from a single length of angleiron material bent V-shaped, there being a cross brace 11 formed of strap material disposed across and connecting the rear ends of the side rails. The vertical webs of the side rails are extended rearwardly and serve as a means for connecting the ends of the cross brace and also as a means for attaching lateral wings 12. These wings are used for attaching other harrows to the harrow be-

ing described in order to produce a gang of harrows.

The harrow toothbeams 13 are each formed of channel iron with the open side directed rearwardly, there being gudgeons 14 formed on the ends of the channel iron and journaled in corresponding openings in the vertical webs of the harrow side rails. The harrow teeth 15 are secured in place by J-bolts 16 which encircle the teeth and pass in the open side of the channel iron and through suitable openings in the channel iron web, as best shown in Fig. 5.

On the leading harrow tooth beam web there is disposed a forwardly projecting spring arm 17, and also on the rearmost harrow tooth beam web there are disposed similar forwardly projecting springs arms 18, such arms forming skids when the harrow tooth beams are rotated to withdraw the harrow teeth, such skids facilitating the transportation of the harrow without the necessity of loading the same upon a wagon. Each skid is curved downwardly as shown at 19 so as to ride easily upon the ground, and is secured at the rear end by a bolt 20, but not necessarily so.

For rotating the harrow tooth beams to withdraw the teeth and protrude the skids, the beams are provided with corresponding upstanding bracket arms 21 which are all connected together by a shift link 22 that is pivotally connected to the brackets by pivot pins 23. There is a stationary bar 24 arranged above the shift bar, and connected at the forward end as shown at 25 to the point of the harrow frame, and connected at the rear end as shown at 26 to the center of the cross brace 11. A shift lever 27 is fulcrumed near the rear end of the stationary bar and is pivotally connected by a pivot pin 28 to the rear end of the shift link. Upon shoving the lever forwardly to its limit of movement the tooth bars will be rotated to extend the teeth downwardly to operative position, and upon the lever being pulled rearwardly to its limit of movement the tooth bars will be rotated to withdraw the teeth and extend the skids downward to operative position.

For locking the shift lever in adjusted positions, an arched strap bracket 29 is secured to the stationary bar and is provided in the top with a series of openings 30 adapted to selectively receive a spring pressed

pawl 31 that is slidably fitted in guides 32 on the lever and is equipped with a handle 33 for withdrawing the pawl. A roller 34 is fitted in the lower end of the pawl and 5 rides upon the top of the strap bracket during shifting of the lever. It will be noted that by virtue of the pawl projecting entirely through the openings in the brackets, slipping of the lever from operative position 10 is positively prevented.

The harrow frame is equipped at the forward end with an upwardly curved arm 35 that is equipped with a ring 36. This ring may be attached to the draft appliance, or 15 in case of plurality of harrows of the above described type are used in the nature of a gang, this ring may be attached to the wing of the adjacent harrow by any preferred means.

20 From the above description it will be seen that I have provided an extremely simple and effective harrow that is formed of a few strong and durable parts which are de-

void of numerous connecting bolts usually employed, and which parts are inexpensive 25 in cost and will not easily get out of order.

What is claimed, is:—

A harrow comprising a frame formed of angleiron in the shape of a V, the sides of 30 said V-shaped frame having the vertical webs extended rearwardly, a cross bar at the rear end of said frame having loops near the ends receiving the extensions of said sides, laterally extending apertured wings 35 connected with the sides of said frame for attaching other harrows to produce a gang, and harrow tooth beams secured upon the sides of said frame.

In testimony whereof, I affix my signature, in the presence of witnesses.

JAMES L. GLAWSON.
